BRAKING DEVICE FOR WHEEL CHAIRS

Hanceal W. Foley, Toledo, Ohio, assignor to
 Gendron Wheel Company, Perrysburg, Ohio, a
 corporation of Ohio

Application February 21, 1946, Serial No. 649,198

1 Claim. (Cl. 188—80)

2

This invention relates to invalid chairs, and an object is to produce a new and improved invalid chair in which the frictional forces between wheel bearings may be varied to regulate chair movement.

Another object of this invention is to provide a simple means for imparting transitory shifting movement to the wheel shaft increasing or decreasing frictional resistance to wheel movement.

A further object of this invention is to provide an invalid chair having a stub shaft moveable laterally in the axle housing in response to set screw operation for regulating resistance to chair movement.

Other objects and advantages of this invention will hereinafter appear and for purposes of illustration but not of limitation, an embodiment of the invention is shown in the accompanying drawings in which:

Figure 1 is a perspective view of an invalid chair embodying the invention;

Figure 2 is a fragmentary sectional elevational view through one end portion of the axle assembly showing the invention in detail; and

Figure 3 is a sectional elevation taken on the line 3—3 of Figure 2.

The illustrated embodiment of the invention comprises an invalid chair 10 having a seat 11 positioned over the rear axle housing 12 by interassociated metallic braces 13 and supported thereon by coil springs 14 connecting the underside of the seat 11 to the axle 12 in a manner to permit a degree of springiness which absorbs the shocks to provide comfortable riding qualities. A foot rest 15 stationarily secured to the forward portion of the seat is further supported by a transverse axle 16 having the small wheels 17 rotatably mounted on the outwardly extending ends. Rigid metallic cross braces 18 interconnects the lower forward axle 16 with the main axle 12 to comprise a sturdy chair frame.

Mounted on the ends of the axle 12 are a pair of large wheels 19 which, ordinarily, are freely rotatable, however, not infrequently, it is desirable to vary the effort required to impart movement to the invalid chair and for such purposes means are provided for increasing or decreasing the frictional forces between rotating parts.

For purposes of clarity description will be made of but one end of the axle section adapted for the adjustments described, it being understood that a similar arrangement may be made in connection with the wheels mounted on the other end of the axle or other axles.

Figure 2 shows an aperture 20 extending axial-

ly in the end portion of the axle housing 12 forming a sleeve section 21. An aperture 22 through the upper and rearward portion of the sleeve section 21 is threaded for engagement with a set screw 23 having an inwardly disposed wedge shaped nose 24 and an outwardly disposed stub portion 25 which is partially threaded for positioning a lock bolt 26 which secures the set screw in the vertically adjusted position when tightened down upon the sleeve surface. It is manifest that turning movement of the set screw 23 in one direction or the other imparts upward or downward movement of said set screw in relation to the axle housing.

15 A stub shaft 27, axially moveable in the sleeve section 21, has a cut-out 28 on the upper inner end portion which provides a flattened shoulder 29 having a vertically disposed aperture 30 therethrough which is operatively engaged by the wedge end 24 of the set screw 23 in the assembled relation.

The lateral open ends of the wheel mounting hub 31 positioned on the end of the stub shaft extending outwardly from the axle housing 12 is 25 enclosed by metallic outwardly facing cup shaped members 32a and 32b in which anti-friction bearings 33 are positioned to operate; at one hub end between the surfaces of the cup shaped member 32a, the stub shaft 27, and the end of the axle housing 21, and at the other hub end between the cup shaped member 32b, the stub shaft and the enlarged head 34 secured to the end of the stub shaft.

It is a well known concept in physics that the 35 forces required to overcome the frictional resistance between surfaces whether static or dynamic bears a proportional relation to the normal pressure between the bodies. Thus it is apparent that when transitory shifting movement is imparted to the stub shaft 27 causing the head member 34 to bear more firmly against the anti-friction bearings 33 the forces required to effect wheel turning movement is increased in proportion to the increased lateral or normal pressure. It is also evident that, as the stub shaft is released for outward shifting movement the normal pressures will be relaxed as a result of such movements which automatically take place.

Transitory shifting movement is imparted to the stub shaft 27 in response to the operation of the set-screw 23 which engages the aperture 30. Set-screw turning movements which results in movement of the nose in the downwardly direction effects the inward displacement of the 55 stub shaft in view of the wedge action between

the set-screw 23 and the aperture 30.

the wedge shaped nose 24 and the peripheral upper edge of the aperture 30, increasing the resistance to chair movements as previously explained. Operation of the set screw in the upward direction liberates the stub shaft for limited outward movement in relief of said normal pressure.

Thus, it is obvious that merely by the operation of the set-screw, the normal contact pressure on the antifriction means may be varied over a wide range for adjusting chair movements.

It is also evident that the wheel and stub shaft may be mounted or removed merely by the operation of the set screw in the upwardly direction a distance sufficient to clear the upper surface of the shoulder 29, freeing the stub shaft for lateral sliding movement.

It is evident that I have invented an invalid chair the movements of which may be readily controlled by the simple operation of a set screw which is within the range of the occupant.

It is to be understood that numerous changes in details of construction, arrangement and operation may be effected without departing from the spirit of the invention especially as defined in the appended claim.

What I claim is:

In an invalid chair, a stationary axle housing having a tubular end portion, a stub shaft having a part fitting said end portion and axially shiftable therein, the free end of said stub shaft extending outside of said tubular end portion, a supporting wheel, a hub member mounted for rotation on the free end of said shaft, a pair of laterally spaced ball-bearing units interposed be-

tween the hub member and stub shaft, one ball-bearing unit engageable with the outer end portion of said tubular end portion, a head member on the outer end of said stub shaft adapted to bear against the other ball-bearing unit, an aperture in that part of said stub shaft inside the tubular end portion, and a set screw on said tubular end portion having a conical end portion engageable with an edge of the stub aperture whereby upon tightening the set screw, axial shifting movement is imparted to the stub shaft for frictionally engaging the ball-bearing units and thus exerting a braking action on the hub.

HANCEAL W. FOLEY.
